Patented Aug. 14, 1917.

UNITED STATES PATENT OFFICE.

ALFRED WILSTAM, OF SOUTH PASADENA, CALIFORNIA.

CENTRIFUGAL PUMP.

1,237,007.

Specification of Letters Patent. Patented Aug. 14, 1917.

Application filed June 1, 1916. Serial No. 101,007.

To all whom it may concern:

Be it known that I, ALFRED WILSTAM, a citizen of the United States, residing at the city of South Pasadena, in the county of Los Angeles and State of California, have invented a new and Improved Centrifugal Pump, of which the following is a specification.

My invention relates to a class of centrifugal pumps in which the centrifugal force, set up in the mass of water within its impeller is utilized to form the necessary pressure, said impeller having its exit openings, comparatively speaking, made small, being so proportioned that the exit velocity of the water from said impeller corresponds to what is generally known as the spouting velocity of water due to its pressure or pressure head.

20 The centrifugal pumps in present use do not embody the above working principle; the exit areas of the impellers are made large, thereby preventing the centrifugal action from setting up any pressure therein, 25 but, acting through the vanes, said impellers throw the water outwardly and keep it there by constantly beating it with the ends of said vanes, which action leaves room for eddy currents and a high water friction, 30 which limit the head and make efficiency low. As is well known, the action within these impellers is kinetic, no static pressure is reached until after the water has left the impellers. By proportioning the diameter 35 and number of revolutions of the impeller I am able to construct my pump so that the peripheral speed of said impeller will closely approach the spouting velocity of the water leaving the impeller, thereby depositing said 40 water into the discharge channel outside the impeller at as low a velocity as practicable.

By my invention I develop the required pressure through centrifugal force generated in the mass of water within the impeller by 45 imparting to the impeller the necessary rotative speed in conformity with the well known centrifugal law expressed by the formula

$$F = \frac{wv^2}{gR}$$

50 and furthermore, I retain that pressure within the impeller by discharging the water through a nozzle shaped opening or openings placed at the periphery of said impeller whose discharge area is proportioned in ac-

cordance with the well known hydraulic law governing spouting or discharge of water under a given head or pressure expressed by the formula

60

$$V = \sqrt{2gh};$$

thereby giving to the discharge area the correct size for letting through the desired amount of water (for which the pump may 65 be designed as to capacity) under a given pressure head.

The pressure energy imparted to the water within the impeller of this centrifugal pump is all transferred into velocity as said water 70 spouts through the nozzles, but as the impeller is moving forward with a peripheral speed only slightly in excess of the rearwardly spouting water jets, it follows that said water, although issuing from the nozzles at a high velocity, and in an opposite direction to the motion of the impeller, in reality is dragging behind the impeller, going in a radial-forward direction relative to the motion of the impeller, and enters the 75 discharge passage at a comparatively low velocity, consequently the imparted pressure energy in the water, which was transformed into velocity in the nozzles, is here almost instantaneously changed into pressure again. 80

85 The head against which the present centrifugal pumps are capable of working is very limited, hence when high lifts have to be accomplished, several pumps have to be connected in series, or, as is usually the case, one 90 pump with several impellers is made, the water working through it in stages. This method is costly and much of the power is lost by water friction. Through my invention, by which a pressure is generated and 95 maintained in the impeller of a centrifugal pump and the water thus energized successfully disposed of, I am able to produce a one-stage centrifugal pump which can work against a head which it now requires a six 100 or more stage pump to do, and while my invention may be successfully used for ordinary centrifugal pump heads, or lifts, it is my principal aim to bring out a practical high pressure single-stage pump. A require- 105 ment of 500 gallons of water per minute against a head of 200 feet or upward would offer an example of the conditions to which I am referring and which my invention is offered to meet and provide for. 110

Referring to the above comparative statement it will be seen that although my pump

of necessity has some resemblance as to form to the present type of centrifugal or turbine pumps, it is clear that the working principle is entirely different.

5 In the drawings forming a part of this application:

Figure 1 is a section on the line 1—1 of Fig. 2.

Fig. 2 is a section on the line 2—2 of 10 Fig. 1.

Fig. 3 is a diagrammatic detail of the vane ring.

Fig. 4 is a detail showing the impeller flanges.

15 Referring to the drawing: Upon the base 5 is secured the outer casing 6 of my improved centrifugal pump, illustrating the application of my invention to a single suction type pump, although it must be understood that I do not wish to limit the scope 20 of my invention to this type alone, and that various departures may be made from the forms of detailed construction herein shown and described without departing from the 25 spirit of my invention. To casing 6 is attached as shown cover 7 which at its center has a cylindrical opening forming the suction inlet 8. Mounted in the casing 6 is the shaft 9 to which the impeller is attached.

30 This impeller is composed of hub 10, casing 11, vanes 12 and walls 13. At the inner ends of said vanes in conjunction with the hub and casing is formed the inlet port 14 through which the water enters the impeller 35 chambers 15 formed by the vanes. Each chamber 15 terminates in a discharge nozzle-shaped opening 16 suitably formed in the end wall 13 through which the water discharges into the stationary vane ring 17.

40 I prefer to call the above discharge opening "nozzle" as its function in this class of centrifugal pump is that of a nozzle discharging under a certain head or pressure.

Fitted to the casing 6 and cover 7, said 45 vane ring consists of a ring member 17 to which are attached the projecting vanes 18, whose function it is to divert the water coming from the discharge nozzles into the discharge passage 19. On the outer sides 50 at the edges of the impeller are rearwardly projecting tangential vanes 20 which rotate in grooves 21 in the outer pump casing or cover, the function of vanes 20 being to deflect back into the discharge passage 19 55 any water which may have a tendency to pass around into the clearance space 23 between the impeller and the outer pump casing, and on the outer side of the edges of the hub of the impeller are forwardly projecting tangential vanes 22 which rotate in 60

grooves 24, located in close proximity to suction inlet 8, the function of vanes 22 being to deflect back into the inlet port 8 any water which may have a tendency to pass up on the outside into the clearance space 23. 65

Having thus described my invention what I claim is:

1. In a centrifugal pump of the class described, an impeller provided with tangential discharge nozzles and inlet ports in the center thereof, and having around the outer edges on the sides thereof rows of rearwardly projected tangential vanes, and at the inlet port a row of forwardly projected tangential vanes. 75

2. In a centrifugal pump of the class described, an impeller provided with tangential discharge nozzles and inlet ports in the center thereof, and having on its sides at the inlet port, a row of forwardly projecting tangential vanes, a stationary outwardly diverging annular discharge passage into which said nozzles discharge, and a stationary vane ring with vanes projecting across said discharge passage substantially 80 as described and shown and for the purpose set forth. 85

3. In a centrifugal pump of the class described, the combination of an impeller with inlet ports in the center thereof and comprising a series of rearwardly curved compartments each terminating at the periphery in a radial end wall having a tangential nozzle whose discharge area is proportioned in accordance with the well known hydraulic law governing spouting or discharge of water under a given head or pressure, expressed by the formula 90

$$V = \sqrt{2gh},$$

100

thereby giving to the discharge area the correct size for transforming into velocity the centrifugal pressure in the water within said compartments, as said water passes through the nozzles, said impeller having 105 around the outer edges on the side thereof rows of rearwardly projecting tangential vanes, and at the inlet port a row of forwardly projecting tangential vanes, a stationary outwardly diverging annular discharge passage into which said nozzles discharge, and a stationary vane ring with 110 vanes projecting across said discharge passage substantially as described and shown and for the purpose set forth. 115

In witness that I claim the foregoing I have hereunto subscribed my name this 25th day of May 1916.

ALFRED WILSTAM.
